UNITED STATES PATENT OFFICE

105,413

DESIGN FOR A CUFF LINK

Samuel Sampson, Woodmere, N. Y., assignor to
Swank Products, Inc., a corporation of Delaware

Application February 17, 1937, Serial No. 67,713

Term of patent 14 years

To all whom it may concern:

Be it known that I, Samuel Sampson, a citizen of the United States, residing at Woodmere, in the county of Nassau and State of New York, have invented a new, original, and ornamental Design for a Cuff Link, of which the following is a specification, reference being had to the accompanying drawing, forming a part thereof.

Fig. 1 is a perspective view of a cuff link embodying my new design;

Fig. 2 is a side elevation thereof.

The dominant features of my design reside in the portion shown in full lines.

I claim:

The ornamental design for a cuff link substantially as shown and described.

SAMUEL SAMPSON.
